H. KOPPERS

CHANNEL OVEN

Filed July 7, 1921

55- Murray Clark Coopertor. A7525

INVENTOR:
Hans Koppers

UNITED STATES PATENT OFFICE.

HEINRICH KOPPERS, OF ESSEN-RUHR, GERMANY, ASSIGNOR TO THE KOPPERS DEVELOPMENT CORPORATION, OF PITTSBURGH, PENNSYLVANIA, A CORPORATION OF PENNSYLVANIA.

CHANNEL OVEN.

Application filed July 7, 1921. Serial No. 483,050.

To all whom it may concern:

Be it known that I, HEINRICH KOPPERS (assignor to The Koppers Development Corporation, a corporation of Pennsylvania), a citizen of Germany, residing in Essen-Ruhr, Germany, have invented a new and useful Improvement in Channel Ovens (for which I have made application for patent in Germany on or about September 10, 1919), of which the following is a specification.

The invention relates to channel ovens for burning ceramic goods, and has for a principal object an improved arrangement 15 and connection of the chambers forming the preheating, burning and cooling zones, whereby the desired flow of the preheating and burning gases and of the cooling air is caused or facilitated, with suitable independence of the cooling zone, and less interruption in the travel of the cars.

In the channel or tunnel ovens for burning ceramic goods, silica, magnesite, dolomite, and the like, requirements of a purely 25 heating character and of an operating nature are opposed to each other. The requirement of as perfect a heating method as possible is best met by a complete separation of the preheating, burning and cooling 30 chambers and zones, while, on the other hand, by as unobstructed a passage as possible of the cars carrying the material to be burnt, through the directly adjoining, individual zones of such a preheating, burning and cooling chamber the 35 simplest operation is effected.

By the invention both of these requirements (as to temperatures and movement) are reconciled with each other by means of 40 a minimum number of necessary locks and their arrangement at the proper place. On the one hand the heating requirements are satisfied in a practical manner and, on the other hand, the smooth operation is permitted or interfered with as little as possible. This is accomplished by effecting (on the basis of the oven so fully embodying the heating requirements according to my 45 German application K. 66532 V/80) only one separation between the said three zones, that is between the burning and the cooling chambers. The restriction to this one separation, and that one at exactly the place

mentioned, is based on the realization that an exchange of the air passing through the 55 cooling chambers with the burning gases entails undesirable interference, while a passage of burning gases into the preheating stage proper is not of such predominating importance, since the latter may be considered a continuation or antechamber of the burning chamber. To this must be added that, at any rate in connection with the burning of highly fireproof stones, special importance must be attached to the 60 careful carrying out of the cooling, because the highly heated stones are exceptionally susceptible to local undercooling.

This separation of the cooling chamber results in the additional possibility of improving the operating conditions for this 70 stage. With the hitherto adopted wholly or at least approximately horizontal placing of such tunnel or channel ovens, the heated gases spread to both sides along the ceiling, 75 with the result that, by virtue of their buoyance, no one single current of the gases enters the oven, but rather a series of whirlpool formations which affect the desired cooling or preheating, especially in the way 80 of retarding the same. By downwardly inclining a cooling chamber thus separated, towards the inlet place of the cold air, an unequivocal current towards the hot end is obtained by virtue of the buoyancy of 85 the cooling air through the hot stones as it absorbs heat. Whirlpool formations are thereby entirely avoided, so that in this direction also the cooling process is controlled in an increased measure.

Such channel ovens themselves have sometimes been given a drop towards the outlet end in order to facilitate moving the cars, carrying the material to be burnt, through the oven. This drop is in itself, however, insufficient to effect such a single direction current as is effected in the present case. If, however, as may not be necessary but at least seems suitable or advisable, the preheating chamber proper has a gradient towards the cold entrance end, what is gained by the aforesaid drop, in the oven chamber, for facilitating the working of the transporting device for the cars, is eliminated by such reverse inclination of the preheat- 100 105

In order to make the invention more clearly understood there is shown in the accompanying drawings means for carrying the same into practical effect, the invention 5 not to be limited to the particular embodiment which is herein used for illustration and explanation. In said drawings—

Fig. 1 is a vertical longitudinal section of a channel oven embodying the invention. 10 Fig. 2 is a substantially horizontal section of the same on line II—II of Fig. 1.

The burning chambers 21, 21', built alongside of each other in accordance with my 15 said German application, and communicating with each other through openings in the central partition, are provided on both sides with the air regenerators 23, 23' and the gas regenerators 24, 24', by means of which an entirely independent and accurately 20 adjustable heating of the burning chamber proper can be brought about. Directly adjoining the burning chamber are the pre-heating chambers 10, 10', to which the cars 30 loaded with the "green" material to be 25 burnt are fed by means of pressure devices 46 after opening the doors 47, 47'. The air 30 gas mixture used for preheating the "green" material is sucked off through the channels 48 into the chimney 49.

30 In the axes of the burning chambers 21 but otherwise separated therefrom, the cooling chambers 11, 11' are provided, which are separated from the burning chambers by doors 34, 34'. For moving these heavy 35 doors a kind of elevated traveling platform 50 is provided which first moves the doors towards each other and then draws them aside to expose the passage openings for the cars. The chambers 11, 11' are strongly 40 inclined towards the exit end and closed by slides 51, 51', and the air supplied here through a conduit 52, flows over the freshly 45 burnt material, cooling it thereby, but becoming heated in turn. Due to the buoyance 50 thus created the cooling air becoming warmer 45 flows in a uniform current towards the higher end of the ovens 11, 11' to be conducted here, through the bridging conduits 55 and the channels 45', to the beginning or starting point of the preheating zone 10, 10', proper. Here the highly heated air is supplied above the cars to be drawn off through the openings 48 at the height of the car surfaces, as illustrated. The uniform 60 distribution hereby brought about over the material to be burnt can be still further strengthened by placing this preheating part of the oven also at a slant towards the cold end as shown.

60 What is claimed is—

1. A channel oven for burning ceramic articles and the like, consisting of a continuous chamber providing preheating and burning chambers; a cooling chamber spaced apart from said continuous chamber; means

for closing and opening the contiguous ends of said continuous and cooling chambers; means for delivering the heated air from the cooling chamber to the preheating chamber; and means for conveying articles 70 through said three chambers.

2. A channel oven for burning ceramic articles and the like, consisting of an upwardly inclined preheating chamber; a burning chamber continuous therewith; a cooling 75 chamber spaced apart from said burning chamber and inclined downwardly from said burning chamber towards the exit end of the cooling chamber; means for opening and closing the doors of the contiguous ends of 80 the cooling and burning chambers; means for conveying articles through said three chambers; means for supplying cooling air to the exit end of the cooling chamber; means for conducting said cooling air from 85 the entrance end of the cooling chamber into the higher end of the preheating chamber; and means leading from the entrance end of the preheating chamber for drawing off the air from the burning and preheating 90 chambers.

3. A channel oven for burning ceramic articles and the like, consisting of a continuous preheating chamber and burning chamber, a cooling chamber spaced apart from 95 said burning chamber, means for closing and opening the contiguous ends of said burning and cooling chambers, and means for conveying articles through said three chambers.

4. A channel oven for burning ceramic 100 articles and the like, consisting of an upwardly inclined preheating chamber in which the heating air flows downward counter to the advance of said articles, and a burning chamber continuous with said preheating chamber, a separate cooling chamber, means for closing and opening the contiguous ends of said burning and cooling chambers, and means for conveying articles 105 through said three chambers.

5. A channel oven for burning ceramic articles and the like, consisting of a continuous preheating chamber and burning chamber, a separate cooling chamber declining 110 downward toward its exit, means for closing and opening the contiguous ends of said burning and cooling chambers, and means for conveying articles through said three chambers.

6. A channel oven for burning ceramic 115 articles and the like, consisting of an upwardly inclined preheating chamber, a burning chamber continuous therewith, a separate cooling chamber declining towards its exit, means for closing and opening the contiguous ends of said burning and cooling chambers, means for heating the burning chamber, means for conveying articles through said three chambers, means for supplying cooling air to the lower end of the 120

cooling chamber, means for conducting said air from the upper end of the cooling chamber and along the burning chamber and into the higher end of the preheating chamber, and a chimney connection leading from the lower end of the preheating chamber.

7. A channel oven for burning ceramic

articles and the like, consisting of a preheating chamber, a burning chamber, a cooling chamber, said cooling chamber being spaced 10 apart from said burning chamber and means for conveying articles through said chambers.

HEINRICH KOPPERS.
